MOVABLE SCAFFOLD SUPPORT

Hillman R. Laviolette, Vidor, Tex.

Application September 26, 1958, Serial No. 763,504

4 Claims. (Cl. 248—323)

This invention relates to scaffolding structures, and more particularly to scaffolding adapted to be suspended from parallel structural elements, such as I-beams, or the like, to support workmen in painting or performing other required operations in a building structure.

A main object of the invention is to provide a novel and improved scaffolding structure which involves simple components, which is easy to set up for use, and which is easy to adjust in position so that it may be readily moved along a building structure which is being painted or upon which other repair or maintenance operations are being performed.

A further object of the invention is to provide an improved scaffolding structure which involves inexpensive components, which is rugged in construction, which is safe to use, and which provides a great saving in time and labor required to paint or perform other operations on a building structure.

Further objects and advantages of the invention will become apparent from the following description and claims, and from the accompanying drawings, wherein:

Figure 1 is a perspective view of a scaffolding structure according to the present invention, shown suspended from a pair of parallel I-beams.

Figure 2 is an enlarged vertical cross sectional view taken on the line 2—2 of Figure 1.

Figure 3 is a vertical cross sectional view taken on the line 3—3 of Figure 2.

Figure 4 is an enlarged cross sectional detail view taken on the line 4—4 of Figure 2.

Referring to the drawings, the improved scaffolding structure is designated generally at 11 and comprises a pair of carriage members 12, 12, each carriage member comprising a rigid frame element 13 having a generally U-shaped outer configuration and formed integral with a central frame member 14 and a pair of transversely extending cross members 15 and 16 connecting the end portions of the central element 14 to the side arm portions of the U-shaped outer part of the frame 13. The top end of the intermediate element 14 projects above the upper cross bar 16, as shown at 17, and is formed with an upstanding pivot lug 18 to which are pivotally connected the arms 19 and 20 for rotation in a plane transverse to the plane of the frame member 13, as is clearly apparent from Figure 1. Pivotally connected to the top ends of the respective arms 19 and 20 are the respective generally L-shaped block members 21 and 22, said block members being threadedly engaged by the oppositely threaded end portions 23 and 24 of a tie rod 25. As shown the tie rod 25 is provided with the enlarged mid portion 26, serving as a handle for rotating the tie rod to adjust the spacing between the block members 21 and 22.

Journalized to the respective block members 21 and 22 are the respective horizontally flanged rollers 27 and 28, said rollers having the enlarged circular top flanges 29 and 30 engageable on the top surfaces of the bottom flanges 31 of the I-beams 32 of a building structure, as

2

shown in Figure 1. As will be readily apparent, the tie rod 25 may be rotated to cause the rollers 27 and 28 to closely engage the edge portions of the bottom flanges 31 of the I-beams so as to retain each carriage engaged with an associated I-beam and whereby to support the associated frame 13 and the load carried thereby.

The side arms of the U-shaped outer portion of each frame member 13 is formed with the outwardly projecting lugs 33, 33, and threadedly engaged through the lugs 33 are the respective vertical shaft members 34, 34. Rotatably secured to the top ends of the shaft members 34, 34 are the respective block elements 35, 35, and journaled to the block elements on opposite sides thereof are the respective pairs of rollers 36, 36 adapted to engage the underside of the associated I-beam 32. Thus, each of the threaded shaft members 34 is provided with a transversely extending bottom handle 37 which may be employed to adjust the shaft members so that the associated pair of rollers 36, 36 closely engage with the under surface of the I-beam 32 on which the associated carriage assembly is mounted, whereby to assure that the carriage engages the bottom flange 31 of the I-beam without excessive looseness, whereby to insure that the carriage member will move smoothly and freely along the I-beam.

As shown in Figure 4, ball bearing assemblies 38 are preferably employed with the horizontally flanged rollers 30 and 29, and similar ball bearing assemblies may be employed with the rollers 36.

As shown in Figure 1, a platform member 39 is supportingly engaged in the lower portion of the pair of frame members 13, 13 the platform member 39 having its respective ends engaged between the lower cross bar elements 15 and the bight portions 40 of the respective frame member 13.

As shown in Figure 3, the spacing between the rollers 27 and 28 may be readily adjusted by rotating the tie rod 25, whereby to separate or bring together the respective block members 21 and 22, depending upon the direction of rotation of the handle element 26 of the tie rod. Thus, the carriage member may be readily engaged on the bottom flange of an I-beam and may be adjusted to closely interfit therewith. After the rollers 28 and 27 have been engaged with the edge portions of the I-beam bottom flange in the manner illustrated in Figure 3, the respective pairs of bottom bearing rollers 36, 36 may be adjusted upwardly to closely engage with the under surface of the I-beam in the manner above described, to insure smooth movement of the associated carriage assembly. Thus, with the scaffolding structure installed in the manner shown in Figure 1, the structure may be readily moved along the I-beam 32 so that the painting or other operation being performed may progress continuously without requiring reconstruction or other modification of the scaffolding until the entire length of the building structure has been traversed, after which the scaffolding structure may be moved to the next portion of the building on which the operations are to be performed.

While a specific embodiment of an improved scaffolding structure has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a scaffolding structure, a carriage member comprising a rigid frame element, a pair of arms pivoted to said frame element, horizontal flanged rollers journaled on said arms and being engageable over the opposite edges of the bottom flange of an I-beam, means ad-

justably connecting the upper portions of said arms together, vertically adjustable support elements on said frame element on opposite sides of the arms, bearing rollers journaled on said support elements and being engageable with the underside of the I-beam, and means on the lower portion of the frame element adapted to supportingly engage a platform member.

2. In a scaffolding structure, a carriage member comprising a rigid frame element, a pair of arms pivoted to the upper intermediate portion of the frame element for rotation in a plane transverse to the frame element, horizontally flanged rollers journaled to the top ends of said arms and being engageable over the opposite edges of the bottom flange of an I-beam, means adjustably connecting the upper portions of said arms together, vertically adjustable upstanding support elements on said frame element on opposite sides of the arms, bearing rollers journaled on said support elements and being engageable with the underside of the I-beam, and means on the lower portion of the frame element adapted to supportingly engage a platform member.

3. In a scaffolding structure, a carriage member comprising a rigid frame element, a pair of arms pivoted to the upper intermediate portion of the frame element for rotation in a plane transverse to the plane of the frame element, horizontally flanged rollers journaled to the top ends of said arms and being engageable over the opposite edge portions of the bottom flange of an I-beam, a tie rod having oppositely threaded end portions threadedly engaged with and adjustably connecting the upper portions of said arms, vertically adjustable upstanding

5 support elements threadedly engaged with said frame element on opposite sides of the arms, bearing rollers journaled on said support elements and being engageable with the underside of the I-beam, and means on the lower portion of the frame element adapted to supportingly engage a platform member.

4. In a scaffolding structure, a carriage member comprising a rigid vertical frame element, a pair of arms extending upwardly and outwardly in opposite directions from and pivoted to the upper intermediate portion of the frame element for rotation in a vertical plane transverse to the vertical plane of the frame element, horizontally flanged horizontal rollers journaled to the top ends of said arms and being engageable over the respective opposite edge portions of the bottom flange of an I-beam, a horizontal tie rod having oppositely threaded end portions threadedly engaged with and adjustably connecting the upper portions of said arms, vertically adjustable upstanding vertical support rods threadedly engaged with said frame element on opposite sides of the arms, bearing rollers journaled on the top ends of said support rods and being engageable with the underside of the I-beam, and means on the lower portion of the frame element adapted to supportingly engage a platform member.
